TWO PART FEEDER BOWL

William V. Spurlin, Indiana, Pa., assignor to Syntron Company, Homer City, Pa., a corporation of Delaware

Application September 25, 1957, Serial No. 686,244

3 Claims. (Cl. 113—116)

This invention relates generally to feeder bowls and more particularly to the construction of the bowls of these feeders.

Feeder bowls are fabricated from sheet metal and are also made of cast aluminum. The fabricated bowls have a conical base and a cylindrical wall. The track is helical and is welded or otherwise secured to the interior of the cylindrical wall. The lower end of the track is welded to the face of the conical bottom of the bowl. The helical track is difficult to form as it has the slope of a flat spring and its inner edge must be fastened to the inner face of the cylindrical bowl at spaced intervals but preferably continuously. This is difficult to do if the diameter of the cylindrical bowl is small and the spacing between adjacent track sections is limited. This type of bowl has considerable material that is not used directly in contact with parts being fed. The gauge of the metal must be such that it cannot flex or vibrate of itself. It must be rigid. It is made up of at least three if not more parts. The bottom is one part, the track can be a second part but it could be fabricated from several sections, and the cylindrical bowl is the last part.

The cast aluminum bowl has a materially greater amount of metal which merely fills in the exterior shape of the bowl. Although the cast aluminum bowl has a spiral track, rather than a simple helix, its exterior is either cylindrical or partly cylindrical and partly an inverted frustum of a cone.

The principal object of this invention is the provision of the method of making and the construction of a feeder bowl. The feeder bowl comprising this invention is made in two parts. The base and the track are made from one integral sheet and the sides of the track that actually make up the bowl is fabricated from one continuous strip of metal welded to the cut edges forming the track. Fastening means are secured to the underside of the bottom to secure the bowl to the motor or base unit. The least amount of metal is thus used to construct this bowl. It is materially less than that of the previously fabricated bowl. This provides for a lighter bowl with good wearing metal such as steel of all kinds or aluminum and other nonferrous metals and alloys.

This method of construction is simple, economical and provides a natural assembly that produces a rigid but light weighted bowl.

Other objects and advantages appear hereinafter in the following description and claims.

The accompanying drawings show for the purpose of exemplification without limiting the invention or the claims thereto, certain practical embodiments illustrating the principles of this invention wherein:

Fig. 1 is a view illustrating a layout on a flat sheet.

Fig. 2 is a sectional view taken along the line 2—2 of Fig. 1.

Fig. 3 is a view of a wall strip to be secured to the track helix which wall strip continues on the helix.

Fig. 4 is a view of a wall strip having a horizontal top.

Fig. 5 is a sectional view showing the completed bowl.

2

Referring to the drawings, the metal plate 1 is provided with the ordinate and abscissa construction lines 2 and 3 which cross at the center 4. A series of center points 5, 6, 7 and 8 are selected at equal radii from the center 4 and midway between the lines 2 and 3 at each quadrant. The midposition in which each of these centers is located would of course be on a line that bisects the quadrant and is 45° from each of the lines 2 and 3.

The plate 1 must be sufficiently large to define the extremities of the bowl. As shown in Fig. 1 the plate is larger than the layout lines.

In order to lay out the spiral track, a radius is struck from the center 5 intersecting the line 2 as indicated at 18. This radius forms the arc 11 and is continued by the increased radius 12 struck from the center 6 forming the arc 13 which is further continued by the radius 14 struck from the center 7 to form the arc 15 from the line 2 to the line 3. The last radius 16 constructs the arc 17 from the line 3 to the line 2 in the last quadrant moving in a counterclockwise direction where the arc 17 struck from the center 8 by the radius 16 intersects the line 2 at a given distance indicated between the points 18 and 20 that represent the desired width of the track. This width is kept constant as between the points 25 and 20 and 21 and along the line 2 as the layout is continued.

Starting with the radius from the point 20 to the center 5 this radius 23 is used to strike the arc 24 through the first quadrant. The radius 25 struck from the center 6 is used to form the arc 26 in the second quadrant 30 and the termination is at point 22 on line 2 from whence the radius 27 from the center 7 is used to strike the arc 28 in the third quadrant and the radius 30 is used to strike the arc 31 in the fourth quadrant ending at the point 21. This completes a full turn of the width of 35 the track starting at point 18 and in order to have one and one-half complete turns of track for the feeder bowl, it is necessary to continue to scribe the helix by striking with the radius 32 from the center 5, the arc 33 in the first quadrant and by the radius 34, the arc 35 in the second quadrant ending at the point 36 on line 2. This 40 completes the layout on the metal plate 1 and the scribed arcs on the plate are then sawed or otherwise cut following from the bottom of the plate 1 along the line 2 to the point 36 and the cutting the spiral starting at point 36 along the arc 35 and continuing through the drawn spiral until the saw blade reaches the point 18 on the line 2. This provides a flat plate with a central portion 40 that has integrally formed therewith a helix in the form of the track 41 that starts at 42 at the plate 40 and 45 ends at 43 between the points 22 and 36.

This flat plate with its integral helix in the form of the track 41 is placed between shaping dies which press the plate and the track into conical form such as illustrated in Fig. 2 which is a section view taken along the line 2—2 of Fig. 1 and shows the different points 18, 20, 21, 22 and 36 providing the track when cut from the plate 1 along the spiral line.

After this plate has been formed in the conical manner as illustrated in Fig. 2 the track 41 is extended so as to open the saw cut following the spiral line. The wall member 44 as shown in Fig. 3 is then welded to the edges forming this saw cut with its point 45 starting at 60 18 and extending around the saw cut with the bottom edge 46 being welded to the bottom plate 40 from the point 18 around to the point 20 whence it leaves the bottom conical plate 40 and extends around the perimeter of the track following the saw cut around the spiral through point 21 and ending at point 36. The end of the strip 44 being sufficiently long so that its opposite end 47 terminates at point 36 of the track 41 as shown in Fig. 1.

The slope as illustrated at 48 in Fig. 3 indicates the initial slope given between the track 41 from the point

18 to approximately one-third of the distance around the first section of the spiral cut after which the width of the strip **44** is of substantial uniform width as indicated at **50** along its upper edge. The upper edge **50** ceases to be welded to the track at point **21** which may be indicated in Fig. 3 at **21**. The upper edge **50** continues then to be free and forms the top surface of the bowl which top surface in the structure as shown in Fig. 3 spirals upwardly with the track.

If a strip **51** such as illustrated in Fig. 4 was employed the starting point **45** and the slope **48** are substantially the same and the bottom edge **46** and the top edge **50** are also substantially the same. However at the end of the position **21** the strip is offset as indicated at **52** which permits the upper rim of the bowl to be horizontal rather than follow the original helix of the track.

As shown in Fig. 5 a bottom **40** and the track **41** have the same pitch. However the helical track has been extended so that the strip **44** may be welded to the opposite edges of the saw cut and the top of the bowl follows the slope of the track as indicated at **50**.

Concentric mounting rings as illustrated at **53** and **54** are provided for securing the feeder bowl to the frame of a vibratory motor. The mounting screw would normally pass down through the bottom of the feeder bowl and the inner mounting ring **53** for bolting the same in position. The mounting ring **53** is slightly higher than the bottom of the mounting ring **54** so that the mounting

bolt will flex the conical bottom and thus function as a tensioning means on the fastening bolt to lock the bowl in place.

I claim:

5. The method of making a feeder bowl comprising the laying out on a flat metal sheet a spiral line of the length equivalent to that of the desired length of the track to form the feeder bowl, cutting the flat sheet along the spiral layout line to make the spiral track independent from the bottom but attached integrally therewith, forming the sheet and the track into conical shape to produce a conical bowl bottom and sloping track, extending the spiral track upwardly to form a helix, and securing a flat strip to the adjacent edges of the extended track to form a bowl, and continuing the flat strip around the perimetral portion of the helically cut edge to complete the rim of the bowl.
10. The method of claim 1 characterized in that said spiral layout line is laid out from quadrant points equidistant from and offset 45° relative to the normal quadrant lines passing through a center.
15. The method of claim 2 characterized in that said quadrant points are gauged to determine the actual width of the spiral track.
